UNITED STATES PATENT OFFICE

159,615

AEROSOL GENERATOR

John W. Hession, Jr., Darien, Conn.

Application January 11, 1949, Serial No. 195

Term of patent 14 years

(Cl. D62—2)

To all whom it may concern:

Be it known that I, John W. Hession, Jr., a citizen of the United States, residing at Edgehill Road, village of Darien, in the county of Fairfield and State of Connecticut, have invented a new, original, and ornamental Design for Aerosol Generator, of which the following is a specification, reference being had to the accompanying drawings, forming a part thereof.

Fig. 1 is a perspective view of an aerosol generator embodying my new design;

Fig. 2 is a side elevational view thereof;

Fig. 3 is a top plan view thereof;

Fig. 4 is a front end elevational view thereof; and

Fig. 5 is a rear end elevational view thereof.

Figs. 1 and 4 show the support in its extended

position, and Figs. 2, 3 and 5 show the support in its raised position.

I claim:

The ornamental design for an aerosol generator, as shown.

JOHN W. HESSION, JR.
